INVENTOR:
JOHN J. EVANS.

BY
Horace Barnes,
ATTORNEY.

UNITED STATES PATENT OFFICE.

JOHN J. EVANS, OF TACOMA, WASHINGTON.

MOLDER'S MATCH PLATE.

1,418,703.

Specification of Letters Patent. Patented June 6, 1922.

Application filed June 9, 1921. Serial No. 476,167.

To all whom it may concern:

Be it known that I, JOHN J. EVANS, a citizen of the United States, and resident of the city of Tacoma, in the county of Pierce and 5 State of Washington, have invented certain new and useful Improvements in Molders' Match Plates, and do hereby declare that the following is a full, clear, and exact description of the same.

10 This invention relates to improvements in match-plates for molding metal castings and in the method of making the same.

The object of the invention is the provision of a match-plate frame of simple construction whereon a pattern of plastic material, or partially of plastic material and 15 partially making use of the original wood pattern, may be formed or secured with beneficial results in the production of castings, and particularly in the molding of articles wherein an even joint is required to be made between the upper and lower parts of the mold-flask.

A further object of the invention is the 20 provision of a simple and inexpensive method of forming the desired pattern on the match-plate frame whereby much time of a skilled pattern-maker is saved and exact results may be obtained.

25 The invention consists in the novel construction, adaptation of parts and combination of elements in a match-plate frame, together with the novel method of forming a pattern thereon, as will be fully described 30 in the following specification, illustrated in the accompanying drawings, and finally pointed out in the appended claims.

In said drawings, Figure 1 is a perspective view of a match-plate frame embodying my invention. Fig. 2 is a similar view 40 of the same with a pattern molded thereon. Fig. 3 is a cross-sectional view of a molder's flask showing the match-plate frame in the sand, substantially as when the pattern is 45 being molded or as when being utilized in molding similar articles in metal. Fig. 4 is a side view of the wooden pattern.

Referring to said views, the reference numeral 1 designates a rectangular cast metal 50 frame having a central opening with integral side walls 2, 2 and end rails 3, 3 of relatively greater width than thickness and with plane upper and lower parallel surfaces. The exterior dimensions of said frame are 55 of the same extent as the similar dimensions of the flask with which it is designed to be

used. 5, 5 indicate integral handles attached to said end rails 3, 3, respectively, each being formed with a triangular aperture 6 arranged to receive the respective aligning 60 posts 7 of the flask, see Fig. 3. A screw 8, or other equivalent device, is operatively mounted in each said handle to bear on said posts whereby the relatively slight but necessary adjustments of the match-plate relative 65 to the flask may be made.

Crossed wires 10 extend across said opening in the frame whose ends are secured rigidly in the side and end rails, respectively, either by being embedded therein as 70 the frame is cast, or in any other suitable manner.

The match-plate frame as described may be used with any of the usual forms of molder's flasks of suitable dimensions, such 75 as that illustrated in Fig. 3, wherein the reference numeral 11 designates the end walls of the lower or "drag" portion of the flask and 12 the end walls of the upper or "cope" portion. The aforesaid aligning 80 posts 7 are secured to said ends 11 of the drag and corresponding ears 13 are provided on the end walls of the cope and are apertured to receive the posts 7 to maintain the flask parts in aligned position. 85

My improved method of making the match-plate and molding a casting therefrom may be described as follows: The wooden or other pattern, see Fig. 4, from which the castings are to be made is placed 90 in the sand 14 of the flask as ordinarily and an impression made therein. The upper or cope portion of the flask is then lifted and the pattern removed. The match-plate frame, shown clearly in Fig. 1, is then superposed on the drag portion of the flask, the apertures 6 receiving the posts 7 of the drag, thereby aligning and maintaining the frame in fixed relative position on the drag. The cope may then be replaced over the 100 frame 1 in the usual manner leaving a space between the upper and lower portions of the flask of the thickness of the match-plate frame. Previously the sand of the cope is formed with a gate 15 and a riser passage 105 16, as well as with depressions, such as 17 and 18, which may be made in the sand of the cope and drag, respectively, to assist in the flow of the plastic material.

A plastic composition having a plaster of 110 Paris base is then poured into the mold through the gate 15 and fills the cavity

made by the lower portion of the pattern in the drag, the space within the frame 1 between the upper and lower parts of the flask, as at 20, see Fig. 3, and in the pattern impression made in the cope, as at 21. The composition is allowed to set for a few minutes whereupon the frame may be taken from the mold and washed with cold water to remove the adhering sand and set in a dry room to harden for about twelve hours.

In this condition the match-plate is ready for use with an exact duplication of the pattern on its opposite sides and is then utilized as a match-plate pattern in the usual manner.

In some instances it may be desirable, to use the original pattern itself or the lower portion of it, as a part of the match-plate. In this case that portion of the pattern 22 utilized is provided with projecting wood-screws 23 protruding thereabove the approximate thickness of the frame 1. In making the match-plate the pattern portion 22 is left in the sand and the screws 23 will protrude through the wires 10. When the plastic material is poured it will surround the screw heads 25 and secure the pattern 22 onto the match-plate in a firm and rigid manner. A metal pattern may be used in a similar manner by employing holding devices analogous to the wood-screws 23.

When the casting work is finished and no further use is to be made of the match-plate, the pattern may be released by unscrewing the screws 23 and the plaster may be knocked out of the frame 1, whereupon the frame may be used again in the same way.

The crossed wires 10 serve to reinforce the plaster filling 20 in the frame opening, and in the event that an uneven joint of the mold 40 interferes with the wires, the latter may be cut and bent to conform to the shape of the mold and the wires thus cut may be tied together about the protruding pattern with additional wire.

The invention is simple in construction and easy of operation and effects a great saving in the production of a match-plate as it does not require the services of a skilled pattern maker and takes but a small fraction of the time at present employed in producing such a device.

Having described my invention, what I claim, is—

1. A match-plate frame consisting in a 55 rectangular metal frame having a central opening, and a plurality of wires fixed in the sides of said frame and crossing said opening.

2. A match-plate frame consisting in a 60 rectangular metal body having a central opening, and a plurality of crossed wires rigidly secured in said body and spanning said opening.

3. A match-plate consisting in a rectangular frame having a central opening therein, crossed wires secured in said frame and spanning said opening, and a filling of plaster composition in said opening reinforced by said wires having a pattern of an object 65 to be cast formed on its upper and lower sides.

JOHN J. EVANS.
